BY *Arthur D. Brown*
ATTORNEY

UNITED STATES PATENT OFFICE

HENRY N. CORDSEN, OF KANSAS CITY, MISSOURI, ASSIGNOR TO SPRINGLESS SHADE COMPANY, OF WICHITA, KANSAS, A CORPORATION OF KANSAS

SHADE BRACKET

Application filed March 22, 1928. Serial No. 263,686.

My invention relates to roller-supported webs such as maps and window shades, and more particularly to means for operating the roller of a device of such character, the 5 principal object of the invention being to rotate the roller by a cord frictionally engaged therewith, to retain the cord in roller-rotating relation, and to support a cord-retaining member from the roller-supporting 10 bracket.

In accomplishing these and other objects of my invention I have provided improved details of structure, the preferred forms of which are illustrated in the accompanying 15 drawings, wherein:

Fig. 1 is a perspective view of a window equipped with a shade embodying my invention.

Fig. 2 is a detail enlarged perspective view 20 of a bracket and one end of a roller in disassembled relation, illustrating the application of a roller-actuator and retaining member thereto.

Fig. 3 is a similar view in detail vertical 25 central section, illustrating the members in functioning relation.

Fig. 4 is an enlarged perspective view of the bracket and clip disassembled.

Referring more in detail to the drawings: 30 1 designates a window having a side casing 2, 3 an awning web wound on a roller 4, and 5 a bracket whereby one end of the awning roller, which is adapted to receive operating means later described, is supported from 35 the side casing 2, the opposite end of the roller being rotatably supported by suitable means in the opposite side of the window.

The bracket 5 comprises a plate 6 adapted 40 to lie vertically along the casing having a slot 7 in its upper end for moving the plate over a nail 8 fixed in the casing adjacent the lintel, and an opening 9 in its lower portion to receive a nail 10 for fixing the bracket to the casing. Projecting from the bracket is 45 a ledge member 11 comprising preferably outbent portions of the plate having a vertical socket 12 to receive a spindle 13 on the illustrated end of the shade roller. The material of the ledge portion is preferably in- 50 bent and arcuate adjacent the socket to pro-

vide a journal member 14 to support the spindle to prevent wear thereof. The roller is, therefore, loosely rotatably supported in the window, and it is further provided with a reduced and peripherally roughened and preferably toothed portion 15 adjacent the spindle comprising a ratchet member for frictional engagement by a cord 16 adapted to run over the toothed member for rotating the roller to wind or unwind the web thereon. A washer or guard 17 fixed on the end of the roller, cooperates with the unreduced end thereof to retain the cord in its channel-like location on the reduced roughened portion. 55

I further provide means for guiding the 60 cord and retaining it in engagement with the ratchet-like member 15, comprising a clip-like member 18 having a body portion 19, and arms 20 and 21 provided with similar 65 arcuate and grooved ears 22 shaped conformably to the cord, the arms and body portions being resilient and adapted for tensionally 70 engaging the cord and the roller to retain the cord in position on the toothed member.

The curved and grooved ears of the clip 75 are spaced substantially by the diameter of the toothed member, and are related to each other for suitable and desired positioning over different areas of the toothed member and preferably the two ears are adapted to 80 be diametrically oppositely positioned on the toothed member. The body member of the clip is adapted to be engaged with the bracket, and for this purpose the lateral ends 23 and 24 of the vertical face portion 25 of the ledge member are preferably bent in- 85 wardly to produce wings extending over the lower shelf 26 produced by the aforesaid out-bending of the plate to form the ledge member, the inner vertical edges of the inbent 90 wings 23 and 24 being inset from the rear face of the plate to provide a seat on said shelf 26 to receive and support the body portion 19 of the clip whereby the body portion has play between the wings and the casing. 95 The arms of the clip extend forwardly outside of the inbent wings and are retained against vertical movement by the uncut extending lateral ends of the ledge member. The arms, further, are bent inwardly towards

each other at points spaced from the face of the ledge member, to provide a recess 27 to receive the washer 17 when the roller is mounted on the bracket, the ears being produced exteriorly to said recess-forming bends.

The fixing of the bracket on the window, therefore, retains the clip in engagement with the bracket, the arcuate arms of the clip extending at right angles to the casing in position to receive the cord and engage the same with the roller.

The lower end of the plate 6 is bent outwardly to provide a stop member for checking upward movement of a window sash that may be slidable in the window.

The device being provided as described, the roller is freely rotatable on its support and can easily be rotated by the cord frictionally engaged with the toothed periphery of the ratchet member adjacent the end of the roller. The clip retains the cord in ratchet-engaging position and tends to enhance the frictional engagement of the cord with the roller, while the cord is sufficiently freely slidable along the inside surfaces of the grooved arms.

The engagement of the body portion and arms of the clip with the bracket stabilizes the clip against strains put thereon by angular portions of the cord when the roller is being operated. Since the body portion of the clip is loosely retained between the wings and the casing, said body portion is bendable, and therefore its resiliency is utilizable for cooperation with the resiliency of the clip arms to promote convenient and efficient functioning of the clip in yieldingly retaining the cord in engagement with the roller.

60 The roller may easily be removed from its supporting bracket, and the arms of the clip may be bent back to admit a fresh cord to the roller.

What I claim and desire to secure by Letters Patent is:

1. In a device of the character described including a roller having a cord receiving portion, and a cord, a bracket comprising a plate having an outstruck portion provided with inbent wings inset from the edges of the plate to form clip receiving notches, means for supporting the roller from the bracket, and a clip engageable in said notches for support from the bracket and engageable with the cord for retaining the cord in operable engagement with the roller.

2. In a device of the character described including a roller having a spindle and a serrated portion, and an operating cord mounted on said serrated portion, a bracket comprising a plate having an offset intermediate portion extending parallel with the plane of the plate and provided with a spindle seat, said portion forming a recess, and a resilient clip mounted in said recess of the plate for

support from the plate and having arms engageable with the cord to retain the same in operative engagement with the roller.

3. In a device of the character described including a roller having a spindle and a serrated portion, and an operating cord mounted on said serrated portion, a bracket comprising a plate having an outstruck portion provided with a spindle seat and side notches, and a resilient clip comprising a body mounted on the plate and having arms extending in said notches for support from the plate, engageable with the cord to retain the same in operative engagement with the roller.

4. In a device of the character described including a roller having a spindle and a serrated portion, and an operating cord mounted on said serrated portion, a bracket comprising a casing plate having an outbent portion forming a recess between the plate and the casing and provided with a spindle seat, and a resilient clip comprising a body mounted behind said outbent portion whereby the plate latches the clip to the casing, and arms extending outwardly from the plate and engageable with the cord to retain the same in operative engagement with the roller.

5. In a device of the character described, including a cord-operated roller and a cord, a bracket comprising a vertically elongated plate adapted to be attached to a window casing and having an intermediate outstruck portion having an instruck spindle seat and forming a recess, vertical edge portions of said outstruck portion being inbent to form clip-receiving notches and clip-stopping edges, and a clip comprising a body seatable in said recess for retention between said edges and the casing, and having resilient arms engageable in said notches and adapted to project from the bracket for engaging the operating cord to urge the cord into engagement with the roller.

6. In a device of the character described, including a cord operated roller and a cord, a bracket comprising a plate adapted to be attached to a window casing, and having a spindle socket and lateral clip-receiving flanges, and a clip comprising a body for mounting between the plate and the casing and outwardly extending arms engageable with said flanges for support from the plate engageable with the operating cord to urge the cord into engagement with the roller.

7. In combination, a roller having a reduced end comprising a cord seat, a cord retaining disk mounted on said reduced end, an operating cord engaging said seat, a roller-supporting bracket, and a clip comprising a body engageable with the bracket and an arm provided with a groove to receive the disk and an extension engageable with the cord for enforcing frictional engagement of the cord with the roller.

8. In combination, a roller having a reduced cord seat, a cord-retaining disk on said reduced end, a roller spindle, an operating cord engaging said seat, a bracket having a spindle-receiving socket and a clip-receiving recess, and a clip comprising a body engageable in said bracket recess for support from the bracket, arms provided with grooves to receive the disk, and means engageable with the cord for enforcing frictional engagement of the cord with the roller.

9. In a device of the character described including a roller having a spindle, and an operating cord mounted on said roller, a bracket comprising a plate having an offset intermediate portion extending parallel with the plane of the plate and provided with a spindle seat, said portion forming a recess, and a resilient clip mounted in said recess of the plate for support from the plate and having arms engageable with the cord to retain the same in operative engagement with the roller.

In testimony whereof I affix my signature.

HENRY N. CORDSEN.
